E. I. HUCKE

PERMANENT RINGLET CURLER

Filed Sept. 14, 1925

INVENTOR:

EUGENIA I. HUCKE,

By: Otto H. Kueger,

her Atty.

Patented Nov. 9, 1926.

1,606,638

UNITED STATES PATENT OFFICE.

EUGENIA I. HUCKE, OF LOS ANGELES, CALIFORNIA.

PERMANENT-RINGLET CURLER.

Application filed September 14, 1925. Serial No. 56,186.

This invention relates to devices used for curling hair.

One of the objects of this invention is to provide a device in which hair may be disposed in ringlets instead of being twisted and wound around tubes.

Another object is to provide a device in which hair can be held in ringlets without supporting cover or holders.

Another object is to provide a device with a hollow into which hair may be disposed in ringlet-form.

Another object is to provide a device with a hollow in which hair may be disposed, being closed except for a comparatively small opening through which the base of a hair-strand may extend while the hair is disposed in the hollow.

Another object is to provide heating means in the ringlet holder.

Another object is to provide electric heating means through one or both handle members of the ringlet holder.

Another object is to provide means for holding oppositely disposed ringlet holders together while hair is disposed between the holders.

Other objects will appear from the following description and appended claims as well as from the accompanying drawing, in which—

Fig. 1 is a top plan view of a pair of holding members connected by a hinge, in opened position, having electric heating connection through one handle, the second holding member receiving the electric connection through the interconnecting hinge.

Fig. 2 is a fragmentary cross section on line 2—2 of Fig. 1, the handle portions being broken away, and the two oppositely disposed holding members being shown in closed position.

Fig. 3 is a cross section on line 3—3 of Fig. 1, taken through the handle portions.

Fig. 4 is a cross section through the handle portions on about the line 4—4, being a slightly modified form of locking means for the handle portions in case the electric heating means is inserted through both handle-positions separately.

Permanent waving of hair is commonly practiced by experts, and at that is rather uncertain and to a great extent unsatisfactory, especially also as to permanency of the produced waves or curls. It is generally

understood that permanent waving results in so-called nigger-wool instead of the more desired and liked ringlets, to compare with natural ringlets.

The device of the present invention is principally intended to produce natural ringlets or ringlets to equal natural ringlets.

As illustrated in the drawing, the device is made of two hair-curling or holding-members 5 and 6, hingedly interconnected at 7, and provided with handle-portions 8 and 9 by which the hair-holding members can be controlled.

Each of the hair holding members is recessed, as indicated at 10, in a circular somewhat concaved manner, so that hair may be disposed between the two holding members fully close around the inserted hair along the edges of the holding members 5 and 6. A portion of the enclosing edges of the holding members is cut away in form of a passage or an opening 11, so that a strand of hair can be disposed through this opening 11 while the larger body of the hair is curled or in a curled condition disposed in the hollow of the hair-holding members.

In the back of the holding members 5 and 6, other cavities 12 are provided, to take care of necessary heating elements 13. The connections for the heating elements may be inserted through the handle member or in any other suitable manner. In Figs. 1, 2 and 3, a construction has been shown, by which the connections may be disposed through one of the handle-members, in this form through the handle member 8, to directly connect with the heating elements in the holding-member 5, while the heating element in the holding member 6 is connected with the heating element in the holding member 5 through the hinge connection 7, the hinge being in this form so designed that the connecting wires may pass around the pivot-pin of the hinge as illustrated in Figs. 1 and 2, without interfering with the operation of the hinge-connection. The interconnecting wires between the two heating-element-sections of the two holders 5 and 6 are indicated at 14.

However, the heating elements in each of the holding members 5 and 6 may be provided with separate connection through the separate handle members 8 and 9, in a similar manner as now illustrated in the handle member 8, without the interconnection at 14.

In the simple form of Figs. 1, 2 and 3, a

simple yoke-like member 15, pivotally connected to the handle member 8, as indicated at 16, serves to lock and hold the handle-member 9 and thereby the holder 6 to the holder 5 in closed position of the device.

In case of having separate connections for the heating elements through each of the handle members 8 and 9, so that the yoke-like lock 15 could not be used, the lock 17 is pivotally connected to swing sidewise over the second handle-member 9_a, to lock this handle member to the handle-member 8_a in a similar manner for closing the hair-holding-members 5 and 6 as described above.

Of course, the hollow 10 can also be provided in one of the members 5 and 6, in which case the other of these members serves merely as a cover for the hollowed section of the hair-holding device.

The principal feature of this device is to provide such a device in which hair can be disposed in ringlet form in a hollow to firmly enclose the ringlets, and in which such ringlets can be properly treated.

The treatment is then merely secondary, and any known treatment can be applied to such ringlets in the enclosure, borax, lanolin, or any other process, and the ringlets can be embedded in cloth, felt, or other mediums for such treatments while held in such hollow of the hair-holder or curler.

The connections 18 for the heating elements are supplied with proper terminations, as electric plugs or the like to fit on the different makes of treatment machines or to be attached directly to the electric sockets of the electric light system of a house. In this manner, this device may either be used as a part of a complicated treatment apparatus of professional estab-

lishments or may be used a single hand-curler in the private home of individual users.

Having thus described my invention, I claim:

1. In a curler, a hair holder made in sections, each having a shallow round recess in its face, so as to receive hair-ringlets and adapted to firmly enclose such ringlets and having heating means for treating the enclosed ringlets. 45

2. In a curler, a closable concaved hair holder having heating means adapted to facilitate treating of hair-ringlets in the concaved holder when disposed therein, the cavity in the holder being of circular and comparatively shallow form with edges to contact so as to seal and firmly enclose the hair during the heat treating. 55

3. In a curler, a hair holder made in sections hingedly connected and having a cavity with edges to abut to firmly enclose hair-ringlets when the hingedly connected sections are closed upon one another with an outlet of comparatively small size for the insertion of the base of the enclosed hair while the hair is so held in ringlet form within the holder. 60

4. In a curler, a hair holder made in sections provided with a cavity with edges to abut adapted to enclose hair-ringlets air and steam tight when the sections are held together, heating means in the holder for heating the holder while hair-ringlets are disposed in the holder, and locking means for holding the sections of the holder so as to firmly enclose the inserted hair-ringlets while treated. 70

In testimony that I claim the foregoing as my invention I have signed my name.

EUGENIA I. HUCKE.
